UNITED STATES PATENT OFFICE.

HENRY BARKSCHAT, OF LOS ANGELES, CALIFORNIA, ASSIGNOR TO MARBELITE CORPORATION OF AMERICA, OF LOS ANGELES, CALIFORNIA, A CORPORATION OF DELAWARE.

CENTRIFUGE AND MOLD HOLDER THEREFOR.

Application filed March 29, 1926. Serial No. 98,176.

This invention has to do generally with machines for molding plastic material by the centrifugal method and has as its principal object to provide holders adapted to be used 5 in connection with such machines whereby articles of unusual configuration or dimensions may be cast.

I will describe the invention in connection with centrifuges for casing elongated articles such as ornamental lamp posts and parts thereof, but this description is merely chosen in order that a clear conception of the invention may be had and is not considered as 10 limitative. In centrifugating ornamental lamp posts two spaced, and substantially axially alined centrifuges are ordinarily employed, one being arranged to grip the elongated mold at each end. Due to their spacing, they are not adapted to take molds of 15 the size usually employed for casting post capitals and the like. The centrifuges have another limitation inasmuch as their chuck holding drums, through which the post molds extend, are of such diameter that they 20 cannot take molds which have any degree of lateral spread, for instance, molds for casting capitals which have wide spreading cross arms.

I have provided means whereby centrifuges which are spaced to take usual post molds may be adapted also to take molds which are of lesser longitudinal extent than the spacing between centrifuge units or having such lateral spread that they cannot be 25 taken within the centrifuge drums. Thus I am enabled to use ordinary equipment for casting these articles of unusual configuration, with obvious economic saving.

Furthermore, the adapter becomes, in 30 effect, the same as an ordinary, elongated post mold, and consequently certain advantages gained in a particular mounting of the elongated post molds in the centrifuges, may also be had in connection with articles 35 held by the adapter.

Further objects and novel features of the invention will be made apparent in the following detailed description, reference being had to the accompanying drawings, in 40 which:

Fig. 1 is a side elevation showing a centrifuge made up of two units equipped with my adapter or holder;

Fig. 2 is an end elevation of Fig. 1;

Fig. 3 is a diagrammatic end view of Fig. 55 1 illustrating certain chuck characteristics;

Fig. 4 is a detached, plan view of the adapter or holder, showing a mold element clamped therein;

Fig. 5 is a section on line 5—5 of Fig. 4; 60

Fig. 6 is a section on line 6—6 of Fig. 4;

Fig. 7 is a section on line 7—7 of Fig. 4;

Fig. 8 is a section on line 8—8 of Fig. 4; and

Fig. 9 is a plan view of the adapter but 65 showing a plurality of mold elements clamped therein.

I will first describe the preferred construction of the holder or adapter, as illustrated in Figs. 4 to 8, inclusive. The adapter may 70 be characterized as a cylindrical holder or cage which is adapted to be parted longitudinally in order that the mold element may be introduced to and withdrawn from the interior of the holder. Considered in its broader aspects, the invention is not limited to the particular construction illustrated, but it is preferable that it be in the nature of a skeleton or frame work so that it may be as 75 light as possible. The skeleton construction is also preferable inasmuch as laterally extending parts of the mold element held therein may project outwardly between the frame members.

As mentioned above, the holder is adapted 80 to be parted longitudinally, and ordinarily it will suffice to have but two of these sections or parts, though this is not a limitation on the invention. In the drawings, 85 holder H is shown as being made up of two substantially symmetrical parts 10 and 11, and it is desirable that all elements of the holder be arranged symmetrically about the longitudinal axis of the holder, when assembled, in order that it may be as nearly as possible in balance. Since sections 10 and 11 90 may be identical, but one need be described in detail. There are two spaced semi-circular heads 12 and 13 which are connected by bars 14, these bars preferably being substantially 95 parallel to the longitudinal axis of the holder and being spaced angularly sufficiently to permit parts "M" of the mold element M (which in the illustrated case consists of a mold for a cross arm capital for ornamental light posts) to project therebetween. While the head and bars may be made of any 100 suitable material and formed in any suitable

manner, I find that by making the heads and bars of wood, the sharper vibrations from the centrifuge which hold them are damped or absorbed before they reach the molded 5 element held therein, and consequently the mold element, ordinarily made of cast metal, is not so readily crystallized or fatigued. Where wood is employed in making up the bars, metal reinforcing strips or plates 15 10 preferably are bolted at 16 along the outer edges of the bars, and the ends of the bars are secured to the heads by bolts or lags 17. Cemented, nailed or otherwise suitably secured to heads 12 are strips 18 of belting or 15 fabric, such materials offering good gripping surfaces for taking the chucks of the centrifuges to be described, and also contributing to the resiliency of the connection between the centrifuges and the mold element where- 20 by vibrations are taken up or damped before they reach the mold element.

Secured to the inner faces of bars 14 are pads 20 of belting, fabric or the like, which are adapted to engage element M, centering 25 and clamping it within the holder when the two holder parts are clamped together. The mold is thus disposed with its longitudinal axis substantially coincident with the axis of rotation of the holder. Due to the resili- 30 ent nature of these pads, they also aid in dampening vibrations before they reach the mold element, and since they are yieldable in nature, do not tend to mutilate or injure the mold even though clamped with considerable 35 tightness thereabout.

Spaced from heads 12 and 13 are substantially semi-circular bands 21 which are secured to the outer faces of bar 14 as at 22. Preferably, diagonal braces 23 extend from 40 bands 21 to adjacent head sections.

With the holder parts separated, mold element M is lowered into position on pads 20, and then the other holder part is lowered onto the mold element, the heads and bands 45 of the two parts being in complementary relation and the bars pressing inwardly upon the mold element with sufficient force to hold it against displacement after clamps 24 have been applied to bands 21. These 50 clamps comprise two substantially arcuate sections 26 and 27 hingedly connected by strips 28 and having terminal flanges 29 through which a clamping bolt 30 extends. When bolt 30 is removed, the clamp parts 55 may be swung apart as shown in dotted lines in Fig. 7 to clear the upper holder-part so it may be moved into and out of registration with the lower holder-part (it being understood that preferably the clamp is entirely 60 detachable from the holder when bolt 30 is removed) while bolt 30 serves to draw the clamp parts tightly together and thereby clamp the holder parts tightly together and in clamping engagement with the mold element.

65 It will be seen that the mold element M is

centered within the holder, and in Fig. 9 I have shown how a plurality of relatively small mold elements M' may be held in centered relation within a single holder 10. With certain types of capital molds, there 70 may be three or even more of such molds supported by a single holder.

While the exact nature of the centrifuges used in connection with the holder is unimportant to the invention considered in its broader aspects, I have shown a type of centrifuge which is especially well adapted for use with the holder. The machine is made up of two substantially identical and axially aligned units 31 and 32, having cylindrical 75 mold carriers or open ended drums 33 and 34, carrying chuck jaws 35 and 36, respectively. These jaws may be arranged in any suitable manner (not shown since many standard jaw actuating means are well 80 known to those skilled in the art) which are adapted to take the ends of usual lamp post molds. Now the longitudinal spacing of units 31 and 32 is such that mold elements M or M' cannot be taken by both chucks 35 85 and 36, nor is the inside diameter of either drum 33 or 34 sufficiently large to take the cross arm portions M'' of mold elements M. However, holder H is of such length that heads 12 and 13 may be taken by chucks 35 90 and 36, respectively, so the holder and hence the mold elements may be rotated in the same manner as the lamp post molds (not shown) which the machine is adapted normally to rotate.

95 Jaws 35 and 36 are movable by any usual mechanism (not shown) to allow easy insertion and withdrawal of heads 12.

Each drum is supported by rollers 37 which are journaled in frames 38 and engage roll-ways 39 in the usual manner. In order that frames 38 need not be built excessively heavy to withstand the vibrations set up by the drums during rotation thereof, it is preferable that roller shafts 37a be yieldably mounted in the frames. For instance, they may be mounted in the manner set forth in United States Letters Patent No. 1,391,164, issued to me Sept. 20, 1921; shaft boxes 40 being slidably mounted for movement in radial paths towards and away from the drum axes and being urged toward said axes by adjustable springs 41.

105 Belts 42 are run over crowned portions 43 of drums 33 and 34, and are driven from power shaft 44 by pulleys 45. While the drawings indicate that both drums are positively driven, it is usually desirable to apply power to one, only, the other merely being guided in its movement by the associated set 110 of rollers 37.

120 Now it is usual to arrange units 31 and 32 so the drum axes are approximately aligned and to hold the mold concentrically in both drums so rotation of the aligned drums causes 125

simple rotation of the mold. However, in a Patent No. 1,544,879 issued to me on July 7, 1925, for "machine for molding concrete posts and the like", I have pointed out that 5 by altering the machine so one end of the mold is gyrated with respect to the other, certain advantageous results are obtained. These results may be briefly summarized as 10 follows: The gyration tends to hasten the disengagement of the excess water in the plastic mass, to hasten the compacting of the aggregate deposited on the mold walls, and to prevent "classification" of the concrete constituents. Since the holder of the present 15 invention becomes, in effect, similar to the molds used in connection with the machine described in the last mentioned patent, it follows that with a machine otherwise similarly arranged to the centrifuges therein described, the holder, and hence the mold elements held thereby, are given the same character of movement as the post molds and the same advantages are gained.

The desired gyratory movement of the 25 adapter may be gained in any one of several manners. For instances, the centrifuge may be altered so that either or both ends of the holder or adapter are eccentrically mounted in the drums. This may be done in the 30 manner diagrammatically illustrated in Fig. 3. Chuck jaws 35 in drum 34 are adapted to hold head 13 concentrically within said drum, while jaws 36 are offset with respect to the axis of rotation of drum 33 and therefore hold head 12 at the left-hand end of the holder (as viewed in Fig. 1) eccentrically within said drum 33. Drum rotation consequently gyrates the ends of the holder with respect to one another, (the chuck jaws being 35 arranged to grasp the holder collars in a manner to allow this relative movement of the mold ends) and hence gyrates the ends of mold element M with respect to one another, with the advantageous effects mentioned above.

It will be understood the drawings and description are to be considered merely as 40 illustrative of and not restrictive on the broader claims appended hereto, for various 45 changes in design, structure and arrangement may be made without departing from the spirit and scope of said claims.

I claim:

1. In a device of the character described, 55 a pair of spaced and substantially axially alined centrifuge units, each having centrally arranged work-taking chucks, and an elongated mold holder adapted to extend longitudinally between the units and to be 60 taken near its opposite ends and to be rotated by said chucks, said holder embodying a plurality of relatively movable sections adapted to take between them a mold element of lesser longitudinal extent than the 65 spacing between units, and releasable means

adapted to hold the sections against relative movement and to clamp the mold element between the sections.

2. In a device of the character described, 70 a pair of spaced and substantially axially alined centrifuge units, each having centrally arranged work-taking chucks, and an elongated mold holder adapted to extend longitudinally between the units and to be taken near its opposite ends and to be rotated by said chucks, said holder embodying a substantially cylindrical, skeleton frame made up of a plurality of relatively movable sections adapted to take between them a mold element of lesser longitudinal extent than the 75 spacing between units, and releasable means adapted to hold the sections against relative movement and to clamp the mold element between the sections.

3. In a device of the character described, 80 a pair of spaced and substantially axially alined centrifuge units, each having centrally arranged work-taking chucks, and an elongated mold holder adapted to extend longitudinally between the units and to be taken near its opposite ends and to be rotated by said chucks, said holder being adapted to support between said units a mold element of lesser longitudinal extent than the spacing between units; there being holder elements of relatively resilient material between the points of chuck engagement and points of mold element support.

4. In a mold holder for centrifuges, a 90 frame embodying spaced and axially alined cylindrical heads, each made up of a plurality of separable parts, a plurality of frame bars extending between and connecting the corresponding sections of the two heads, said bars extending in substantial 95 parallelism with the common head axis and being radially spaced from said axis, the heads being adapted to be parted for the introduction of a mold element between said bars, and releasable means adapted to engage the bars to hold said head parts against 100 separative movement and to clamp the mold element between the bars.

5. In a device of the character described, 110 an elongated and substantially cylindrical mold holder adapted to support a mold element substantially in axial coincidence therewith, and means at two longitudinally spaced points along the holder adapted to rotatably support said holder in a manner to gyrate 115 said points with respect to one another and thereby to gyrate one end of the mold element with respect to the other end.

6. In a device of the character described, 120 a pair of spaced and substantially axially alined centrifuge units, each having centrally arranged work-taking chucks, and an elongated mold holder adapted to extend longitudinally between the units and to be taken near its opposite ends and to be rotated 125

by said chucks, said holder embodying a substantially cylindrical, skeleton frame made up of a plurality of relatively movable sections adapted to take between them a mold element, and releasable means adapted to hold the sections against relative movement and to clamp the mold element between the sections.

7. In a device of the character described,
10 a pair of spaced and substantially axially aligned centrifuge units, each having centrally arranged work-taking chucks, and an elongated mold holder adapted to extend

longitudinally between the units and to be taken near its opposite ends and to be rotated by said chucks, said holder being adapted to support between said units a mold element; there being holder elements of relatively resilient material between the points of chuck engagement and points of mold element support.

In witness that I claim the foregoing I have hereunto subscribed my name this 8th day of March, 1926.

HENRY BARKSCHAT,
